GATE PULL

Dothan L. Shelton, Amarillo, Tex.

Application January 27, 1958, Serial No. 49,419

Term of patent 14 years

(Cl. D10—8)

FIG. 1

FIG. 2

FIG. 3

Figure 1 is a top plan view of a gate pull, showing my new design;

Figure 2 is a side elevational view; and

Figure 3 is an end view thereof.

I claim:

The ornamental design for a gate pull, substantially as shown.
